UNITED STATES PATENT OFFICE.

WILLIAM E. PARK, OF SEBASTOPOL, CALIFORNIA.

RAILWAY SIGNAL APPARATUS.

Application filed April 15, 1925. Serial No. 23,386.

My invention relates to electric railroad crossing signals, and in particular to an electric signal which is operated intermittently in the vicinity of a highway crossing upon the approach of an electric trolley vehicle.

More specifically my invention has for an object the provision of signal devices at a crossing and a plurality of contact devices located at predetermined points adjacent the trolley at either side of said crossing, together with means comprising circuits and a relay for operating said signal upon the closure of certain of said contacts.

15 A further object is to provide a crossing signal which is comparatively simple in construction, reliable in operation, and effective as an alarm.

Other objects will appear from the detailed description of the invention which follows.

In the drawings:

Figure 1 shows a wiring diagram of the various elements of the signal system and the relation of the parts at the instant that the trolley wheel passes a contact corresponding to a position of silence of the relay.

Fig. 2 is a similar view showing the position of these same parts at the instant the trolley wheel passes under the next succeeding contact and wherein the relay has moved to a position to operate the signal.

Fig. 3 shows a modified wiring diagram wherein a storage battery or separate source of electric energy is used to operate the relay and signal.

Fig. 4 shows, in schematic form, the relative positions of relay and signal devices and the related circuits when direct current from the trolley is used to operate these parts.

Fig. 5 is a similar view corresponding to the modification of Fig. 3, showing the wiring of signal devices when the same are operated from a separate source of alternating current or battery current supply.

Fig. 6 is a view of my improved relay, and

50 Figs. 7 and 8 are detail views of contacts adapted to be used with the circuits of Figs. 3 and 1, respectively.

Referring to the drawing in detail, A¹ to A⁵ indicate a plurality of contact devices or trips mounted above and close to a trolley wire T, the lower or middle contact of each trip being connected in direct electrical con-

tact with the trolley wire T. A feeder L¹ is connected to alternate trips A¹—A³—A⁵, and a second feeder L² is connected to the remaining trips A²—A⁴ etc. Relay R is 60 shown in Fig. 1, and on a larger scale in Fig. 6, and comprises a left-hand pair of solenoids and plungers S¹—S³ wired in parallel, and a right-hand pair of solenoids S²—S⁴, also in parallel. The plungers are 65 connected as shown to a cross bar of non-conducting material, each end of which carries a contact shoe O—O¹, the upper shoe O¹ when moved to the right bridging plates 4 and 5, and plate 4 is grounded at G. The 70 lower shoe O in its left-hand position bridges plates 1 and 2, and when moved to the right, bridges plates 2 and 3. Plate 2 is also grounded at G¹. Feeder L¹ is connected to plate 3 through solenoids S¹—S³ in 75 parallel, by wires 7, 8, and feeder L² is connected to plate 1 through solenoids S²—S⁴ in parallel, by wires 10, 11. A lighted crossing sign X and pilot lamp L are arranged at each side of the highway, and a siren H, 80 operated by motor M, is placed adjacent the crossing, and this series of signals is connected permanently in parallel and to the trolley wire on one side by wire 12, and on the other side to plate 5 by wire 13. Fuses 85 f are shown in the relay and signal circuits.

In Fig. 1, while the trolley wheel W has just operated trip A¹, no current will flow from trolley wire T through this trip and feeder L¹, because the circuit to ground G¹ 90 through wires 7 and 8 is open at plate 3. The signals, therefore, will remain silent while trolley wheel W travels from A¹ to A². When, however, as shown in Fig. 2, trip A² is operated, feeder L² is energized 95 from the trolley wire T, and current flows through wire 9 to feeder L², wire 10, solenoids S²—S⁴ in parallel, wire 11 to plate 1; and, since shoe O is at its left-hand position as in Fig. 1, said current passes through this shoe to plate 2 and ground G¹. Solenoids S²—S⁴ pull the plungers over to the right, and as shoe O leaves plate 1, the energizing circuit just traced is broken at this plate. Shoe O¹ has also moved to the right, and a 100 circuit is made from the trolley wire through the signals, as follows: wire 12, signals X, L, M, wire 13, plates 4, 5 and shoe O¹ to ground G. The signals operate during the period it requires trolley wheel W to 110 pass from trip A² to A³. When the latter trip is operated by the trolley wheel, feeder

L^1 is energized from the trolley wire, and circuit is made through wire 14, feeder L^1 , wire 7, solenoids S^1-S^3 , wire 8, plates 2, 3 and shoe O to ground G, and the plungers 5 are again pulled to the left-hand position, which breaks the signal circuit at plate 5. This sequence of operation is repeated as trips A^4-A^5 are operated to produce an intermittent series of signals, each of a definite 10 duration.

In the modification shown in Fig. 3, substantially the same system is employed, with the exception that a third feeder L^3 is used, which feeder is constantly energized by storage battery B. Trips A^1 to A^6 are shown with two upper contacts 32 adapted to be bridged by a lower contact 27, when a trolley wheel W pushes any rod 26 upwardly. Trips A^1 to A^5 etc. alternately connect feeder L^3 to feeders L^2 and L^1 , and current will flow from the battery to one or the other of the latter two through the corresponding pair of solenoids, and back to the battery through wire 20.

25 In Fig. 3, just as in Fig. 1, no current is flowing through trip A^1 , since the current from L^3 through the trip contacts, feeder L^1 and wires 7 and 8 is open circuited at plate 3. When however the trolley wheel 30 passes trip A^2 , current flows from battery B through wires 15, 18, 19, L^2 , 10, and solenoids S^2-S^4 to wires 11 and 20 through plates 1 and 2 and back to battery. The solenoids are pulled to the right breaking 35 the mentioned circuit at plate 1 and a circuit is made at plates 4, 5 by shoe O^1 and current flows from the battery through the signal devices and wires 22, 23, 20 back to battery.

40 When the trip A^3 is operated, current will flow from battery to feeder L^3 , trip A^3 , feeder L^1 and wires 7, 8, then from plates 3 to 2 through shoe O^1 and wire 20 back to battery and the plungers will move again to 45 the left to break the signal circuit at plate 5.

It is obvious that instead of using D. C. battery current to operate the signals a separate source of A. C. current could be used to operate said signals by causing plates 4, 50 5 and shoe O^1 to complete a similar circuit from the A. C. supply and wires 15, 23 would be connected to said A. C. supply instead of to battery B. The device in Fig. 3 will be used when the trolley voltage is too high for 55 signals.

Fig. 4 shows in schematic form a pair of crossing signs X—X and pilot lamps L—L. I prefer to use a sign 36 inches long and about 6 inches wide with red glass on each 60 side. Wire 12 leads from the trolley wire to an appropriate switch and the current will divide at said switch and pass through fuses y—y' to the lights and siren motor M and then to relay plate 5. In case the line 65 voltage is higher than the motor voltage, a

switch lever s may be moved upwardly to insert a resistance r in series with the motor circuit.

Fig. 5 also shows a schematic plan of elements and appropriate wiring employed 70 with a battery or separate A. C. current for operating the signals. Wires 21, 23 lead from a source of A. C. or D. C. current supply through two pole switches to the various signals and the circuits are made and broken 75 at relay plates 4—5.

Fig. 6 shows in detail the elements of my novel relay as explained above.

Fig. 7 shows in detail a form of trip 80 adapted to be used with the battery circuit in Fig. 3. A hardwood case 25 has mounted therein a rod 26. A plate 27 is mounted on rod 26 and insulated therefrom at 34. Terminals 32 are connected to plates 31. The trip casing may be supported from either a 85 catenary or span supported trolley wire and rod 26 may be connected to the trolley wire by any common form of trolley ear.

Fig. 8 shows a form of trip adapted for 90 use in connection with the device of Fig. 1. A metallic rod 26' is connected to the trolley wire and is moved upwardly thereby so as to cause plates 27' and 29 to contact. Metal caps 28, 28' are adjustably mounted on the trip casings and set screws 33 are used to 95 hold said caps in any desired position.

I claim:

1. In a railway crossing signal system, an electrical signal device, a trolley wire, a plurality of contact devices adjacent said 100 trolley wire adapted to be successively operated by a trolley wheel, a double throw relay, circuits associated with said contacts and relay adapted to be alternately energized a plurality of times upon the successive 105 operation of said contacts, contacts on said relay adapted to be operated by successive throws of said relay in one direction and a circuit including said signal device adapted to be intermittently energized 110 upon successive closures of said last named contacts.

2. In a railway crossing signal system including a trolley wire, a plurality of contactors adjacent said trolley wire adapted 115 to be successively operated by a passing trolley wheel, a double coil relay, a circuit associated with one coil of said relay and certain of said contactors for energizing said coil and a circuit associated with others 120 of said contactors and another coil of said relay for energizing said other coil, said coils adapted to be alternately energized a plurality of times by the successive operation of said contactors, contacts on said relay and a signal circuit to be energized by said contacts intermittently to provide a series 125 of alarms.

3. In a railway crossing signal system including a trolley wire, a series of contacts 130

adjacent said wire adapted to be successively closed by a passing trolley wheel, a relay and signal devices controlled thereby, circuits associated with said relay and signal devices respectively, said relay circuit including alternate ones of said contactors, a plunger on said relay and movable intermittently in the same direction a plurality of times upon the energization of said relay by the closure of said alternate contactors, contacts operated by said plunger, said contacts being in series with said signal circuit whereby the later is energized intermittently a plurality of times to provide a series of alarms.

4. In a railway crossing signal system including a trolley wire, a series of contactors adjacent said trolley wire, a relay in circuit with said contactors and operable intermittently a plurality of times by the successive closures of said contactors by a passing trolley wheel, a contact adapted to be closed by successive movements of said relay in one direction and a signal device in circuit with said contactors operable intermittently a series of times upon the successive closures thereof by said relay.

5. In an electric railway crossing signal system, a signal circuit, a trolley wire, a series of contactors adjacent said wire operable successively by the passage of a trolley wheel, a double coil relay, a plurality of circuits including certain ones of said contacts and one coil of said relay and a plurality of circuits alternating with said first mentioned plural circuits and common to another coil of said relay, said circuits being alternately energized by the successive closures of said contactors to operate said relay a plurality of times each way alternately, and contacts closable by successive throws of said relay in one direction to energize said signal circuit to provide an intermittent alarm.

In testimony whereof I have affixed my **45** signature.

WILLIAM E. PARK.
